UNITED STATES PATENT OFFICE

162,535

WRAPPING PAPER FOR BREAD LOAVES
OR THE LIKE

Quinn J. Hagedorn, Dayton, Ohio, assignor to
The Specialty Papers Company, Dayton, Ohio, a corporation of Ohio

Application December 31, 1948, Serial No. 150,471

Term of patent 3½ years

(Cl. D59—2)

To all whom it may concern:

Be it known that I, Quinn J. Hagedorn, a citizen of the United States of America, residing at Dayton, in the county of Montgomery and State of Ohio, have invented a new, original, and ornamental Design for a Wrapping Paper for Bread Loaves or the like, of which the following is a specification, reference being had to the accompanying drawing, forming a part thereof, and in which the figure is a plan view of a piece of wrapping paper showing my new design.

I claim:

The ornamental design for a wrapping paper for bread loaves or the like, substantially as shown.

QUINN J. HAGEDORN.
